(57) **CLAIM**

The ornamental design for a remote control scooter with four wheels, as shown and described.

DESCRIPTION

FIG. 1 is a perspective view of a remote control scooter with four wheels showing my new design;

FIG. 2 is another perspective view thereof viewed from another viewing angle;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the remote control scooter with four wheels as shown in FIG. 1 being folded in a closed position thereof; and,

FIG. 10 is another perspective view of the folded remote control scooter with four wheels as shown in FIG. 9 viewed from another viewing angle.

The broken lines are for the purpose of illustrating portions of the article that form no part of the claim.
